Primary Examiner — Calvin E Vansant*Assistant Examiner* — Mark T. Philipp(74) *Attorney, Agent, or Firm* — Mitchell M. Musial,
PLLC(57) **CLAIM**

The ornamental design for a radial bearing, as shown and described.

DESCRIPTION

FIG. 1 is a front perspective view of the radial bearing of the present disclosure;

FIG. 2 is a bottom perspective view of the radial bearing of FIG. 1;

FIG. 3 is a top plan view thereof;

FIG. 4 is a bottom plan view thereof; and,

FIG. 5 is a side view thereof.

The features shown in broken lines in the various Figures are for illustrating environmental structure and form no part of the claimed design. The surface is lined for contour only.

1 Claim, 2 Drawing Sheets(56)
